Primary Examiner — Karen S Acker(74) *Attorney, Agent, or Firm* — Buchanan Ingersoll & Rooney PC(57) **CLAIM**

The ornamental design for a mesh panel, as shown and described.

DESCRIPTION

FIG. 1 is a perspective view of a mesh panel illustrating my new design.

FIG. 2 is a front elevational view thereof, the rear view being a mirror image.

FIG. 3 is a top plan view thereof.

FIG. 4 is a side elevational view thereof, the other side being a mirror image; and,

FIG. 5 is an enlarged detail of area 5 circumscribed on FIG. 2. The broken lines surrounding the detail areas in FIGS. 2 and 5 are for illustrative purposes and form no part of the claimed design.
